SEWING MACHINE INSTALLATION

Harry L. Willis, Grand Rapids, Mich., assignor to
 Union Special Machine Company, Chicago,
 Ill., a corporation of Illinois

Application May 31, 1933, Serial No. 673,734

5 Claims. (Cl. 311—13)

The invention relates to new and useful improvements in a sewing machine installation, and more particularly to the means for supporting the sewing machine and the material stitched thereby.

5 An object of the invention is to provide a supporting table structure for sewing machines adapted to perform successive stitching operations on fabric sections whereby a fabric section 10 as it is stitched by one of said machines is delivered into a storage receptacle and thus rendered accessible to an operator stitching said sections on the other of said machines.

In the drawings—

15 Figure 1 is a plan view showing a section of a supporting table with sewing machines mounted thereon which are adapted to perform successive stitching operations on fabric sections, and

20 Fig. 2 is a sectional view on the line 2—2 of Fig. 1.

25 It is often desirable to follow the stitching operation on the fabric section with another stitching operation of a slightly different character. When these stitching operations require about the same length of time, it is also desirable to feed the fabric sections stitched on one machine into a receptacle which is readily accessible to the operator for the other machine. For example, in the attaching of the sleeves to a shirt body, the sleeves are joined to the shirt body on one machine and then the sleeves and the side seams are closed on a felling machine. These

30 two operations take about the same length of time. The present illustrated embodiment of the invention shows two machines, one of which is adapted to stitch the sleeves to the body portion of the garment, and the other is adapted to close the sleeves and body portion of the shirt by felling. The first-named machine is mounted

35 on a table carried by a supporting frame structure. The table is located at one side of this frame structure. Also mounted on the frame structure at the rear side of this table is a receptacle adapted to receive the body garment and sleeves after they have been stitched together. At the other side of the supporting frame is a

40 table section for supporting a feed-off-the-arm felling machine. This table section is so constructed and the machine so disposed that the operator sitting in a normal position for feeding the sleeves and shirt body along the work arm for felling, can reach the receptacle and take a

45 stitched garment therefrom and direct it through the felling machine.

50 Referring more in detail to the drawings, the

present illustrated embodiment of the invention includes a supporting frame structure, at one side of which is mounted a table section 1. The frame structure consists of cross frame units, each of which includes supporting legs 2 and 3 connected by a cross beam 4 at the top and by a cross beam 5 at a short distance from the lower end of the legs. These parts are bolted together making a very rigid structure, and the table 1 is bolted to these cross frame units. Mounted in the cross beams 5 are suitable bearing brackets in which the main actuating shaft is located. This table 1 only extends part way from the upper edge of the cross frame toward the center thereof. Attached to the table and cross frames is a sheet metal receptacle 8. This receptacle 8 is provided with a rear wall 9 which extends up to the under side of the table 1, and the table is preferably recessed along its rear edge so as to overlie this wall 9. The vertical wall 9 extends into a curved bottom wall 10 which terminates 20 in a rolled bead 11. This rolled bead 11 is disposed at a considerable distance beneath the upper edge of the receptacle. There are end wall members in the receptacle which are shaped to conform to the cross section of the receptacle and support the bottom wall. The purpose of the bead 11 is not only to strengthen the bottom plate of the receptacle, but also to provide a rounded portion to prevent the operator from 30 injuring the hand when reaching into the receptacle.

25 Mounted on the table 1 is a sewing machine consisting of a work supporting member 12 over which is a needle head 13, and in this needle head is a needle bar 14 carrying needles, one of which is indicated at 15. Beneath the work support is a feeding mechanism, the feed dog of which is indicated at 16. This feed dog operates to feed the material straight across the work support 1, delivering the material off from the rear edge thereof on to the table and off from the table into the receptacle 8. The stitching mechanism may be of any desired character. In the form shown, the machine is adapted for 40 producing a felled seam. The guide 12a is used for interfolding and directing the fabric sections to the stitching mechanism, and a two-needle stitching mechanism is used for joining the interfolded fabric sections.

45 This sewing machine is driven by a belt wheel 17 operated by a belt running over a belt wheel in a transmitter 18, and the transmitter is driven by a belt 19 from a belt wheel 20 on the main actuating shaft 7. The transmitter is controlled 50

by a treadle 21, and the presser bar of the sewing machine is under the control of a treadle 22. The operator sits at the right of the table 1 as viewed in Fig. 2, facing the machine. First one sleeve and the shirt body is passed through the machine 5 and the sleeve stitched to the shirt body. The front and back of the shirt is previously joined to the yoke at the shoulder seams. After one sleeve has been attached to the shirt body, then the other sleeve is attached thereto, and the shirt body with the two sleeves attached is fed into the receptacle 8 at the rear of the table section 1.

Extending at right angles to the table 1 is a cross table 23. This cross table 23 is mounted in part on one of the cross frame units and in 15 part on a supporting standard 24. The table 23 has a lateral extension on which the sewing machine 25 is mounted. This lateral extension is shaped to conform to the supporting base of the sewing machine, and the standard 24 is arranged 20 so that it is directly beneath the base of the sewing machine. The sewing machine shown is a feed-off-the-arm felling machine. Said machine includes a supporting bracket 26 on which the sewing machine proper is supported. Said sewing machine includes an upper horizontal member 27 having a depending portion 28 at the lower end of which is a work supporting arm 29. At the opposite end of the horizontal member 27 is a laterally projecting arm 30 carrying a needle 25 head 31 in which the needle bar 32 reciprocates, and said needle bar carries two needles which are indicated at 33. Mounted in the needle head is a presser bar carrying a presser foot 34, and in front of the presser foot is a felling guide 33a. 35 The machine illustrated is of the type shown in the Christensen and Le Vesconte Patent #1,741,-095, granted December 24, 1929. The operator sits adjacent the suspended end of the work supporting arm as indicated at C, and the feed 40 is off from the end of the arm so that the operator may place the fabric sections to be stitched about the arm and direct the same through the feller to the stitching mechanism.

The stitching mechanism and the feeding mechanism of the sewing machine is all operated 45 from an actuating shaft in the upper horizontal member 27 and the shaft is driven by a belt wheel 36 which in turn is operated by a belt 37 running over a pulley in the transmitter 38, and the transmitter is driven by a belt 39 cooperating with a belt wheel on the main actuating shaft 7. The transmitter is controlled by a foot treadle 40 and the presser foot is controlled by a foot 50 treadle 41.

In the operation of the present illustrated installation, first one sleeve is joined to the body portion of the garment by the sewing machine at the right, as viewed in Figures 1 and 2, and then the other, and the joined sleeves and body 55 portion of the shirt drop into the receptacle 8. The operator for the sewing machine at the left reaches into the receptacle, taking one garment at a time, and directing the same around the work support 29 to the stitching mechanism, 60 whereby the sleeve seam and the body seam are felled at one side of the shirt body and then the sleeve and the body seam are passed through the machine and felled at the other side of the shirt body. If, for any reason, the operator of 65 the felling machine is delayed in the passing of the fabric sections to the machine, they will accumulate in the receptacle 8. The operator can readily reach the receptacle into which the 70 articles are discharged by the feed of the machine 75

at the right in the drawings. In this way, there is substantially a continuous flow of the fabric sections, first through the machine which joins the sleeves to the body portion, and thence through the machine wherein the sleeve and body seams are formed.

The invention is, of course, not limited to the present illustrated embodiment of the specific types of machines described. It may be used in connection with sewing machines of any character wherein the articles being stitched are 10 passed through first one machine and then another in succession for stitching operations. The essential feature of the invention is in the arrangement of the stitching machines so that the articles passing from one machine will be fed 15 into a storage receptacle and may be taken from the storage receptacle which is made readily accessible to the operator of the other machine for feeding said machine.

It is obvious that changes may be made in the 20 arrangement of the parts and the details of construction without departing from the spirit of the invention as set forth in the appended claims.

Having thus described the invention, what I 25 claim as new and desire to secure by Letters Patent, is—

1. In a sewing machine installation, the combination of spaced cross frame members, a main actuating shaft carried thereby, a supporting table arranged at one side of said cross frame 30 members on which a sewing machine is adapted to be mounted and positioned to feed sewed articles toward the inner side of the table, means for actuating said sewing machine from said shaft, a work receptacle carried by said table and 35 cross frame members and adapted to receive and store the stitched articles fed from the sewing machine, said receptacle being disposed wholly beneath the plane of the work supporting table 40 and extending from a position adjacent the rear underface of the table downwardly and thence rearwardly and thence upwardly and terminating at a point well beneath the table to facilitate the removal of the articles therefrom, a supporting 45 member carried by said cross frame and projecting outwardly beyond said work receptacle on which a second sewing machine is adapted to be supported, and means for operating said second machine from said actuating shaft, said second 50 machine being positioned on said supporting member so as to feed the articles sewed thereby substantially at right angles to the feed of the material to and from the first machine whereby an operator may be positioned close to the work 55 receptacle for removing the stored articles one at a time therefrom and feeding the same to said second machine.

2. In a sewing machine installation, the combination of spaced cross frames, a supporting 60 table arranged at one side of said cross frames on which a sewing machine is adapted to be mounted and positioned to feed sewed articles toward the inner side of the table, a work receptacle carried by said cross frame members and disposed at the inner side of said table and adapted to receive the stitched articles fed from said sewing machine, said receptacle being formed of sheet metal and including a rear wall extending 65 upwardly to the lower side of the table, a curved bottom wall extending upwardly at the front of the receptacle and terminating in an edge located in a plane well below the plane of the table, 70 said edge being rolled into a hollow bead, and 75

end walls attached to and supporting said bottom wall.

3. In a sewing machine installation, the combination of spaced cross frames, a supporting table arranged at one side of said cross frames on which a sewing machine is adapted to be mounted and positioned to feed sewed articles toward the inner side of the table, a work receptacle carried by said cross frame members and disposed at the 10 inner side of said table and adapted to receive the stitched articles fed from said sewing machine, said receptacle being formed of sheet metal and including a rear wall extending upwardly to the lower side of the table, a curved bottom wall extending upwardly at the front of the receptacle and terminating in an edge located in a plane well below the plane of the table, and end walls attached to and supporting said bottom wall, and a supporting 15 table at the opposite side of said frame and the front side of said receptacle adapted to support a sewing machine disposed thereon so that the operator operating the machine may readily reach into the receptacle for removing the 20 stitched articles therefrom for feeding the same to the second machine.

4. In a sewing machine installation, the combination of spaced cross-frames, a supporting table arranged at one side of said cross-frames on 25 which a sewing machine is adapted to be mounted and positioned to feed sewed articles toward the inner side of the table, a work receptacle carried by said cross-frame members and disposed at the inner side of said table and adapted to receive the

stitched articles fed from said sewing machine, said receptacle including a rear wall extending upwardly to the lower side of the table, a bottom wall extending laterally and thence upwardly at the front of the receptacle and terminating in an edge located in a plane well below the plane of the table, and end walls attached to and supporting said bottom wall. 5

5. In a sewing machine installation, the combination of spaced cross-frames, a supporting 10 table arranged at one side of said cross-frames on which a sewing machine is adapted to be mounted and positioned to feed sewed articles toward the inner side of the table, a work receptacle carried by said cross-frame members and disposed at the inner side of said table and adapted to receive the stitched articles fed from said sewing machine, said receptacle including a rear wall extending upwardly to the lower side of the table, a bottom wall extending laterally and 15 thence upwardly at the front of the receptacle and terminating in an edge located in a plane well below the plane of the table, end walls attached to and supporting said bottom wall, and a second supporting table at the opposite side of 20 said frame and at the front side of said receptacle adapted to support a second sewing machine disposed thereon so that the operator operating the said second machine may readily reach into the receptacle for removing the stitched articles 25 therefrom for feeding the same to the said second sewing machine.
